(57) **CLAIM**

The ornamental design for a spa mounted solar chlorine generator, shown and described.

DESCRIPTION

FIG. 1 is a perspective view of a spa mounted solar chlorine generator showing my new design.

FIG. 2 is a side elevational view thereof.

FIG. 3 is a rear elevational view thereof.

FIG. 4 is a front elevational view thereof.

FIG. 5 is a top elevational view thereof; and,

FIG. 6 is a bottom elevational view thereof.

The broken lines shown in the figures illustrate environmental elements of the design in position of use, and form no part of the claimed design. The other side elevational view is a mirror image of that shown in FIG. 2.
